(57) **CLAIM**

The ornamental design for a cartridge, as shown and described.

DESCRIPTION

FIG. 1 is a perspective view of a cartridge in an open configuration showing our new design;

FIG. 2 is a front view of the design of FIG. 1;

FIG. 3 is a back view of the design of FIG. 1;

FIG. 4 is a first side view of the design of FIG. 1;

FIG. 5 is a second side view of the design of FIG. 1;

FIG. 6 is a top view of the design of FIG. 1;

FIG. 7 is a bottom view of the design of FIG. 1;

FIG. 8 is a perspective view of a cartridge in a closed configuration showing our new design;

FIG. 9 is a front view of the design of FIG. 8;

FIG. 10 is a back view of the design of FIG. 8;

FIG. 11 is a first side view of the design of FIG. 8;

FIG. 12 is a second side view of the design of FIG. 8;

FIG. 13 is a top view of the design of FIG. 8; and,

FIG. 14 is a bottom view of the design of FIG. 8.

The broken lines depict portions of the cartridge that form no part of the claimed design.

1 Claim, 14 Drawing Sheets
